METHOD FOR FORMING SHAPES FROM
SHEET METAL

Malcolm C. Durbin, Jamaica, N. Y.

Application December 10, 1936, Serial No. 115,130

2 Claims. (Cl. 113—116)

This invention relates to a method for forming shapes from sheet metal and a particular object of the invention is to form shapes from sheet stock that has square corners and a further object of the invention is to form shapes from sheet stock by displacing the metal at the corners so as to provide a groove at the inside of the bend in the stock and to provide outside corners that may be trimmed off square with the surface of the sheet stock. Other objects of the invention will be more particularly understood from the following specification and from the accompanying drawing, in which—

Fig. 1 is an end view of sheet stock formed in a channel in which part of the process of this invention has been used;

Fig. 2 is a cross section of a channel shape formed according to this invention and used as a cover or shield for a channel iron;

Fig. 3 is an end view of a shape such as is commonly used on door jambs constructed according to this invention;

Fig. 4 is an end view of a rectangular form of tube made according to this invention;

Fig. 5 is an elevation of a pair of dies used to form the corners of the sheet stock which is shown in section in the dies, and

Fig. 6 is a form of abrasive belt that may be used to trim the corners after the bending operation when square corners are desired.

In architectural and ornamental work it is common practice to provide a veneer of sheet metal, such as brass, bronze or aluminum on doors, windows and the like and for this purpose the trade has provided a variety of shapes which are made by extruding dies, or by a drawing process and in each case special dies are required for each shape, the stock has to be manufactured in quantities and stored, and in general the cost of the shapes is comparatively high.

The structural steel shapes are produced according to standard sizes by the rolling mills but light angles and channels are now generally produced from sheet stock in a break. This process enables the shapes to be formed from sheet stock as required and without the application of heat.

Shapes formed on a break from sheet stock always have round corners as the stock is bent around a mandrel and the thickness or cross section of the stock at the corners is the same as in the body. For many purposes, particularly of an ornamental character, square corners are required on the shapes which cannot be produced in the ordinary process by a break with the result that shapes of this type have to be extruded or

produced by some of the more expensive methods. It is the purpose of this invention to provide a break equipped with a die that will displace the stock at the corner from the inside towards the outside of the bend providing protrusions on the outside at the corners that provides a fillet at the outer apex of the bend sufficient to provide a square corner when the protrusions are ground away flush with the surface of the stock. In addition to this a groove is provided on the inside of the corners instead of the usual curved fillet so that shapes bent in this way can be applied to other members having a sharp edge.

In addition to providing stock formed into shapes with square corners, the working or drawing operation of the dies on the corners of non-ferrous metals hardens the metal at this point with the result that a comparatively rigid construction, capable of resisting ordinary shocks at the corners, is obtained in shapes formed according to this process.

Shapes with square corners can be formed into frames for doors and the like and where the shapes meet the edges are flush and the seam can be concealed. While the process herein disclosed is particularly adaptable for non-ferrous metals, it may also be used for sheet steel constructions.

In the drawing, 11 indicates a strip of sheet stock which is bent upwards at the sides as indicated at 12 and 13 to form a channel. The inner corners are provided with grooves shown at 14 and 15 and the outer corners, as indicated in Fig. 1, have rounded protrusions indicated at 16, which extend below the surface 17 of the sheet stock.

A channel made in this form can be applied to a structural steel channel 19, Fig. 2, without trimming the corners of the steel channel. This is due to the fact that the grooves 14 and 15 provide a clearance for the sharp corners of the channel 19, making a snug fit between the covering channel 17 and the structural channel 19. In Fig. 2 the outer channel has the corners trimmed off flush at 18 with the outer surfaces of the stock 12, 13 and 17, thereby making square or right angle corners.

The shape in Fig. 3 is designed for a door jam which may be provided with the supporting member 20. This shape, 21, has a central extension 23 and is provided with sides as indicated at 22. It will be observed that the outer corners 24 are trimmed off square, making a sharp edge and that the inner corners of the bends indicated by 25 are formed in a groove corresponding to the grooves 14 and 15, Fig. 1.

The shapes may be made in a variety of forms, the usual plan is to form one bend at a time with the groove in the corner and afterwards to progress by subsequent bends of push out type described herein; all bends do not have to be of this type as at times it is desirable in certain shapes to have one or more of the usual break (round corner bends) in the sequence. This arrangement has been followed in forming the rectangular tube, Fig. 4, in which the tube is formed from a single piece of sheet stock having the sides 26 and 27, the bottom 28 and the wings 29 and 30, at the top. Each corner is formed with the groove 32 on the inner side of the bend and when the shape is finished the outer corners are trimmed off square as indicated at 31. The last operation in forming this shape is indicated by the dotted lines in which the sides 26' and 27' 20 are brought into position by straightening out the curved bottom member 28' with the usual flattening die.

One form of die that may be used in practicing this invention is illustrated in Fig. 5 in which the upper die member 51 of the break registers with the lower die member 52 and engages the stock 11 between these members, subject to the pressure of the machine. The lower member is formed with a curved pocket 53 which is opposed by the curved spud 54 of the top die. The pressure on the top die not only bends the stock 11 and 12 into a right angle, but it forms a groove corresponding to 56 on the inner side of the bend and it displaces the metal of the stock into the protrusions 55—55. The dotted lines indicate the plane of the outer surfaces 11 and 12 which meet at their apex within the protrusions 55 so that as the protrusions are ground away flush with the surfaces 11 and 12, a sharp corner is provided at 40

the apex, which is indicated in Fig. 5 on an enlarged scale.

The construction in Fig. 6 is a diagram of a belt-type grinder that may be used to trim the protrusions on the outside of the corners. This 5 comprises the belt wheel 68, mounted on the shaft 59, and the companion belt wheel 69 mounted on shaft 61, with the abrasive belt 62 mounted on these wheels and suitably driven by means not shown in the drawing. The belt passes over the 10 channel 11 and is held in alignment by the guide 64. Under these conditions the belt grinds away the protrusions 55 on the edges of the channel until the bottom of the channel is level. The operation is then repeated with reference to the 15 sides 12 and 13, thereby removing the surplus material at the corners and leaving a square edge. When brass or other non-ferrous metals are used the corners 63 that are "worked" by the die are thereby hardened and the lasting qualities of the 20 shape are increased.

Having thus described my invention, I claim:

1. A method of forming shapes having a plurality of square corners from sheet metal comprising bending the stock at each corner in a die 25 arranged to displace the metal from the inside of the corner to form protrusions on the outside of the corners, grinding away the protrusions to form the square corners and bending the stock to the final shape desired. 30

2. A method of forming a rectangular shape having a plurality of square corners from sheet metal comprising bending the stock at each corner in a die arranged to displace the metal on the outside of the corner so that the stock will 35 fill the apex of the square corner to excess on the outside, bending the stock to shape, and grinding away the excess stock to align with the adjacent sides.
